UNITED STATES PATENT OFFICE.

FREDERIC RAMSAY, OF ELGIN, ILLINOIS.

HEEL ATTACHMENT.

1,403,523.

Specification of Letters Patent. Patented Jan. 17, 1922.

Application filed October 18, 1919. Serial No. 331,605.

To all whom it may concern:

Be it known that I, FREDERIC RAMSAY, a citizen of the United States, and a resident of the city of Elgin, county of Kane, and 5 State of Illinois, have invented certain new and useful Improvements in Heel Attachments, of which the following is a specification.

My invention relates to new and useful 10 improvements in heel attachments and has for its object the provision of a heel attachment whereby the wearing surface of the heel may be worn uniformly on all sides.

Other objects will appear hereinafter.

15 The invention consists in the combinations and arrangements of parts hereinafter described and claimed.

The invention will be best understood by reference to the accompanying drawings 20 forming a part of this specification, and in which,

Fig. 1 is a vertical sectional view of my invention applied to a heel.

Fig. 2 is a top plan view of the wearing 25 member of my invention.

Fig. 3 is a plan view of a heel embodying the attaching means of my invention.

Fig. 4 is a vertical sectional view of a heel 30 showing my invention attached with a rubber wearing surface.

Fig. 5 is a sectional view taken on substantially line 5—5 of Fig. 4.

The approved form of construction comprises a wearing member 6 which is made 35 circular in form. Attached to the upper surface of the member 6 by suitable fastening means 8 is a circular metallic disk 7. The heel 9 of the shoe with which my invention is applied is formed circular in cross 40 section and has attached to it by means of nails 10 or other suitable means a disk 11 projecting upwardly from which, and adapted to seat in a recess formed in the heel of the shoe, is an interiorly threaded 45 socket member 12. The wearing member 6 is provided with an opening 13 and the member 7 is provided with an opening 14 having beveled edges which are adapted to engage the head of a screw 14' which is 50 threaded into the socket 12. After securing the socket bearing member to the shoe the wearing member 6 may be secured therein by means of the threaded member 14' being threaded into the member 12 so as to securely 55 clamp the member 7 against the lower surface of the heel and the disk 11.

The surface of the member 7 which engages the lower surface of the member 11 is provided with a series of recesses 15 which are adapted to engage the heads of the nails 60 10. In use one side of the wearing member is subjected to greater wear than the remaining portion and consequently becomes worn more quickly than the remaining portion. By my invention I provide 65 means for subjecting the entire surface of the wearing portion to the same wear or strain. When one portion of the wearing surface becomes a little worn the member 14 is threaded out of the socket 12 sufficiently to allow disengagement of the recesses 15 from the heads 10. The wearing surface may then be rotated a sufficient distance to present a new wearing surface at that point where the greatest wear or strain 70 75 is exerted. The member 14' is then threaded into the member 12 so as to cause the heads of the nails 10 to again engage in the recesses 15 which thereby prevent rotation of the wearing member while the same is 80 being used.

In Fig. 4 I have shown my invention applied to a rubber wearing surface. When a rubber wearing surface 16 is used the metallic disk 7 and its connecting means 8 are 85 dispensed with and a metallic plate 17 having a number of perforations 18 therein is mounted in the rubber. The member 17 is provided with a central opening 19 through which the threaded member 14' is adapted 90 to pass. The perforations 18 allow the rubber 16 to protrude therein and thereby securely hold these members in fixed relative position. When the member 14' is threaded into the socket 12 the heads of the nails 95 10 are embedded in the rubber 16 and thereby prevent rotation of the same while being used.

While I have illustrated and described the preferred form of construction for 100 carrying my invention into effect, this is capable of variation and modification without departing from the spirit of the invention. I, therefore, do not wish to be limited to the precise details of construction set 105 forth, but desire to avail myself of such variations and modifications as come within the scope of the appended claim.

Having described my invention, what I claim as new and desire to secure by Letters 110 Patent is:

A heel attachment comprising a socket

member provided with screw threads on its inner face, an outwardly extending flange on the lower end portion of said socket member, headed members for securing said flange on the lower face of a heel for holding the socket member fixedly in vertical position within an opening in the heel, a wearing member comprising a metal plate, and a screw passing through an opening in said plate for securing the wearing member to said socket member below said heel, said

headed members being adapted by engagement with said wearing member to hold the wearing member against rotary movement with respect to the heel.

15

In testimony whereof I have signed my name to this specification in the presence of two subscribing witnesses.

FREDERIC RAMSAY.
